UNITED STATES PATENT OFFICE.

LUTHER WEBESTER SHIPMAN, OF GREENVILLE, SOUTH CAROLINA.

WORK-MARKING TOOL.

Application filed November 6, 1924. Serial No. 748,188.

To all whom it may concern:

Be it known that I, LUTHER W. SHIPMAN, a citizen of the United States, residing at Greenville, in the county of Greenville and State of South Carolina, have invented certain new and useful Improvements in Work-Marking Tools; and I do declare the following to be a full, clear, and exact description of the invention, such as will enable others skilled in the art to which it appertains to make and use the same.

My invention relates to improvements in tools adapted to be set in numerous ways for use by carpenters, in marking straight and oblique cuts, circles, etc., the tool being readily adapted for use in laying out rafters.

The object of the invention is to provide a simple and inexpensive tool of the class set forth, yet one which will be very efficient and desirable and may be easily operated.

With the foregoing in view, the invention resides in the novel subject matter hereinafter described and claimed, the description being supplemented by the accompanying drawings.

Figure 1 is a side elevation of a marking tool constructed in accordance with my invention.

Figure 2 is an edge view.

Figures 3, 4 and 5 are transverse sectional views on lines 3-3, 4-4 and 5-5 of Fig. 1.

Figures 6 to 10 inclusive are diagrammatic elevations showing different ways of using the tool.

In the drawings above described, the numeral 1 designates a square having two blades 2 and 3 disposed at right angles to each other, the inner edges of said blades 40 preferably having scales 4 and 5 respectively, while their outer edges are provided with similar scales 6 and 7. The two blades are provided with central longitudinal slots 8 for a purpose to appear.

Extending across one flat side of the square 1, is a straight bar 9 having a relatively wide longitudinal slot 10, while disposed parallel with the bar 9, at the opposite side of the square, is a second bar 11 having a relatively narrow longitudinal slot 12. At one end, the bars 9 and 11 terminate in inwardly spaced relation with the outer edge of the blade 2 and are preferably cut obliquely as indicated at 13, so that they 55 will not interfere with proper marking along said edge of said blade. At their

outer ends, the bars 9 and 11 project outwardly from the square and are glued or otherwise suitably secured against opposite sides of a spacer 14. These ends of the 60 bars are also provided with a straight transverse arm 15 which is secured at right angles thereto. The edges of the bars 9 and 11 are provided with suitable scales 16 and 17.

Passing through the slots 10 and 12, I have shown a fastening screw 18 which also passes through one of the slots 8 of the square. This screw is preferably provided at one end with an operating head or 70 thumb piece 19 and with an outstanding annular flange 20, between which and the bar 11, a washer 21 may well be placed. The other end of the screw 18 is threaded through a rectangular nut 22 which is slidably received in the slot 10 and is preferably provided with a transverse indicating mark 23 for co-action with one or the other of the scales 16 and 17. The end of the screw, last referred to, preferably projects beyond 80 the bar 9 and is brought to a sharp point, as indicated at 24. When this screw is loosened and is adjusted any desired distance from the cross arm 15, the device may be used as a gauge as illustrated in 85 Fig. 7, and the pointed end 24 of the screw, will act to mark the work, as indicated by the black line in that figure. When the device is so used, the cross arm 15 acts as a guide to engage the edge of the piece of 90 lumber being marked.

The relatively short edge of the bar 9 is formed with an elongated notch 25, disposed adjacent the outer edge of the blade 2, and received normally in this notch, is a 95 block 26 which is adapted to be longitudinally extended from the bar 9 so as to extend to or beyond said outer edge of said blade 2. This extended position of the block 26 is disclosed in Fig. 8, and it may 100 here be explained that the block is extended so that it may co-act with the scale 6, in properly setting one end of the short edges of the bars 9 and 11 with respect to the scale 6, or at the desired distance from the inner end of the blade 2, while the scale 7 is employed for co-action with either the long or short edges of said bars 9 and 11 for properly setting the ends of said bars 105 adjacent the cross arm 15. After the proper setting has been accomplished, the block 26 is again returned to a position 110

within the notch 25 so that it will not interfere with proper marking along the outer edge of the blade 2.

Carrying the block 26, I have shown a metal plate 27 which contacts with the outer side of the bar 9 and is provided with a lateral flange 28 received in a longitudinal groove 29 in said bar. This plate is formed with a slot 30 parallel with the groove 29 and flange 28, and a screw 31, which passes through the bars 9 and 11 and through the slot 8 of the blade 2, also passes through said slot 30. At one end, the screw 31 is formed with a thumb-piece 32 by means of which it may be rotated, and with an outstanding flange 33, while the opposite end of said screw is pointed as indicated at 34, and threaded through a clamping nut 35. It will be seen that the single screw 31 serves to normally hold the plate 27 in its retracted position (Fig. 1), as well as clamping the bars 9 and 11 against opposite sides of the blade 2 of the square 1.

The device may be used in numerous ways, some of which are illustrated on sheet 2 of the drawings. Fig. 6 illustrates the manner in which the cross arm 15 may coact with one of the bars 9-11, in permitting the formation of a mark straight across one edge 25 of a rafter or other piece of lumber. This same general relation of parts may be employed, when the device is to be used as a try-square. Fig. 7 illustrates the manner of using the device as a gauge, after first setting the screw 18, the proper distance from the cross arm 15. The tool may well be used as a gauge when it is necessary to rip the lower end of a rafter along a given line, to permit substantially half the vertical 40 width of said rafter to project beyond a cap plate, to form eaves.

Figure 8 discloses the manner in which the tool may be employed for marking the side of a rafter, and while in this figure, the plate 27 and the block 26 have been shown in projected position, they are in reality retracted when the tool is used in the manner set forth, so that they will not obscure the edge mark on the rafter, which mark has been previously made by using the tool in the manner shown in Fig. 6. When so retracted, it will also be seen that the parts 26 and 27 will not interfere with marking the side of the rafter entirely to the edge thereof.

In Fig. 9, the bars 9 and 11 have been swung into alinement with one of the blades of the square 1, so that one of them may contact with one edge of a piece of lumber, the cross arm 15 may rest on the latter, and the other blade of the square may extend across

it, for guiding a pencil in making a line for a square end cut.

By adjusting the screw 18 to any desired distance from the screw 31, one of them may act as a center and the other as a scribe, for marking circles, as shown in Fig. 10.

It will be seen from the foregoing that while the device is simple and inexpensive, it will have a wide range of uses and will be generally efficient and desirable. As excellent results are obtainable from the details disclosed, they are preferably followed, but within the scope of the invention as claimed, minor changes may of course be made.

I claim:

1. A work marking tool comprising a square having two blades at right angles to each other, the outer edge portions of said blades having scales, a bar adapted to extend obliquely from one blade to the other, means slidably connecting the bar and blades one end of said bar terminating in inwardly spaced relation to the outer edge of one blade, and a block slidably mounted on said one end of said bar and having one edge in alinement with one edge thereof, said block being adapted to be extended from said bar end to cross one of the aforesaid scales when setting the bar along the blades of the square.

2. A work marking tool comprising a square having two blades at right angles to each other, the outer edge portions of said blades having scales, a bar slidably on one of said blades and having one end disposed in inwardly spaced relation to the outer edge of the other blade, means interconnecting the bar and said blade said one end of the bar having a notch in one of its corners, a block received normally in said notch with one edge in alinement with the adjacent longitudinal edge of the bar, a slide plate contacting with one face of said bar and carrying said block to permit the latter to be extended across the outer edge of said other blade, said bar having a longitudinal groove and the plate being formed with a laterally extending flange received slidably in said groove, and a releasable fastener passing through said bar, said plate and said other blade, the plate being formed with a slot receiving said fastener and disposed parallel with the aforesaid flange, said other blade having a longitudinal slot receiving said fastener.

In testimony whereof I have hereunto affixed my signature.

LUTHER WEBESTER SHIPMAN.
